UNITED STATES PATENT OFFICE.

GEORGE F. KEENE, OF WHITMAN, MASSACHUSETTS, ASSIGNOR TO UNITED SHOE MACHINERY COMPANY, OF PATERSON, NEW JERSEY, A CORPORATION OF NEW JERSEY.

STITCH SEPARATING AND INDENTING MACHINE.

1,232,427.

Specification of Letters Patent.

Patented July 3, 1917.

Application filed December 5, 1912. Serial No. 735,114.

To all whom it may concern:

Be it known that I, GEORGE F. KEENE, a citizen of the United States, residing at Whitman, in the county of Plymouth and State of Massachusetts, have invented certain new and useful Improvements in Stitch Separating and Indenting Machines; and I do hereby declare the following to be a full, clear, and exact description of the invention, such as will enable others skilled in the art to which it appertains to make and use the same.

This invention relates to machines for indenting the interval between the stitches of a finished seam, and for shaping the crowns of the stitches so as to impart a uniform and finished appearance to the seam. Such machines are known in the art as stitch separating and indenting machines.

One object of the present invention is to produce a stitch separating and indenting machine for indenting the intervals between the stitches of a finished seam to separate the stitches and for shaping the crowns of the stitches in a novel and improved manner.

In certain classes of high-priced shoes the outsole is attached to the insole by means of a very coarse unwaxed thread which is sewn in comparatively long stitches. The stitches of the seam formed with this coarse unwaxed thread in the above manner, as they appear along the upper surface of the welt, are very white, and on this account, and because of the coarseness and loose texture of the thread, impart a striking and attractive appearance to the upper surface of the outer margin of the sole. It has been found that by first indenting the interval between the stitches of a seam sewed with wax thread, and then crushing down the crowns of the stitches which have previously been separated while the separation between them is substantially unobstructed, the stitch separations are partially obliterated, and the thread at the crowns of the stitches is flattened or "squashed" out, so as to cause the seam to appear very similar to a seam sewed with coarse unwaxed thread, and it is another object of the invention to produce a stitch separating and indenting machine for performing the above operations.

With the above objects in view, the invention comprises certain novel and improved features clearly set forth in the following

description and pointed out in the claims 55 appended thereto, the advantages of which will be obvious to those skilled in the art.

The features of the invention will be readily understood from an inspection of the accompanying drawings taken in connection 60 with the following description.

In the drawings illustrating the invention in its preferred form, Figure 1 is a front elevation of a stitch separating and indenting machine embodying the invention;

Fig. 2 is a detail front elevation of the lower or acting portion of an indenting tool;

Fig. 3 is a detail view in side elevation of the acting portion of the tool;

Fig. 4 is a diagrammatic view illustrating the acting portion of the tool and the margin of the sole of the shoe in section and showing the action of the tool upon the stitches; and

Fig. 5 is a diagrammatic view showing the marginal portion of the sole in plan and illustrating the effect of the tool upon the stitches.

With the exception of the indenting tool 80 the parts of the machine illustrated in the drawings are the same in construction, arrangement and mode of operation as the corresponding parts of the machine illustrated in the patent to Hadaway No. 543,012, 85 dated July 23, 1895, to which patent reference may be had for a full and complete description of the parts which are but briefly described in this application.

In the drawings, 1 indicates the lower 90 work support, 2 the upper work support which engages the upper surface of the margin of the sole, and 3 the edge gage for engagement with the edge of the sole. 4 is the tool stock upon which the indenting tool 95 is supported, 5 the lever upon which the tool stock is pivotally mounted, 6 the spring which acts on the lever 5 to press the tool lightly against the work during the locating movements of the tool, 7 the feed slide by 100 which the locating and feeding movements are imparted to the tool, 8 the presser lever which actuates the lever 5 to force the tool into the work, and 9 the lever which actuates the lever 5 to raise the tool from the 105 work.

During the cycle of operation of the machine, starting immediately after the feed

movement of the work has taken place, the indenting tool is first moved lightly into engagement with the work, then has certain lateral or locating movements imparted thereto to cause the indenting blade to find the interval between the stitches, is then forced into the work with considerable pressure to separate the stitches, is thereafter moved laterally to feed the work, and is finally raised out of engagement with the work. These movements are the same as the movements imparted to the tool in the machine of the patent referred to above.

As illustrated in Figs. 2 and 3, the indenting tool is provided with an indenting blade 10 for insertion in the interval between the stitches to separate the stitches and with a surface 11 arranged in advance of the indenting blade or extending from the indenting blade in the direction of the feed movement of the work for engaging and shaping the crown of at least one stitch in advance of the indenting blade while the indenting blade is located in the interval between two stitches. The crown engaging surface 11 of the tool is preferably flat or nearly so, and is arranged substantially perpendicular to the indenting blade.

In the sewing machine at present in commercial use for sewing outsoles to the uppers of boots and shoes, the longest stitch which can be made upon the machine is substantially one-eighth of an inch in length, and the indenting tool of the present invention is preferably constructed so that when operating upon a seam having eight stitches to an inch, the crown shaping surface 11 of the tool will extend over the first stitch in advance of the indenting blade and at least half way over the crown of the second stitch in advance of the blade while the indenting blade is located in the interval between two stitches. The tool might be constructed so that the surface 11 extended completely over the second stitch in advance of the blade, but it has been found that a tool constructed in accordance with the preferred embodiment of the invention as above stated, produces the desired effect in shaping the crown of the stitches. It will also be apparent that when the machine is operating upon a seam having more than eight stitches to the inch the surface 11 of the tool will extend more than half way over the crown of the second stitch in advance of the indenting blade.

The manner in which the finished seam is acted upon by the tool will be apparent from an inspection of Figs. 4 and 5. When the tool is forced lightly against the work the blade 10 rests upon the tops of the stitches, the other portions of the tool being supported out of contact therewith. As the locating movements are imparted to the tool 65 the blade 10 finds the interval between two

stitches and rests therein in the usual manner. When the tool is forced down on to the work the indenting blade is forced into the interval between two stitches to separate the stitches, and the surface 11 of the tool 70 engages, crushes down and shapes the crowns of the two stitches in advance of the indenting blade in the direction of the feed movement of the work. Fig. 4 shows the position of the tool with relation to the 75 work after the indenting blade has been forced into the work. The stitches indicated at *a*, *b*, *c* and *d* have been previously separated by the indenting tool, and the crowns of the stitches *a* and *b* have been 80 completely shaped by the tool. The crown of the stitch *c* receives its final shaping while the indenting blade is located in the interval between the stitches *d* and *e* to separate the stitches, as shown in Fig. 4. The crown 85 of the stitch *d* is partially shaped by the crown engaging surface of the tool while the indenting blade is located in the interval between the stitches *d* and *e*, and will receive its final shaping when the indenting 90 blade is indenting the interval between the stitches *e* and *f* to separate these stitches. Prior to the actuation of the indenting tool to force the indenting blade down into the interval between the stitches *d* and *e*, the 95 crowns of the stitches *c* and *d* had substantially the forms of the crowns of the stitches *d* and *e* respectively, as shown in Fig. 4; that is, the crown of the stitch *c* was crushed down flat, the stitch interval to the left of 100 the stitch *c* was nearly obliterated, a separation of substantially the same width and shape as the separation between the stitches *d* and *e* as shown in Fig. 4 appeared between the stitches *c* and *d*, and the crown 105 of the stitch *d* had substantially the natural rounded shape of the stitch *e*. When the tool was actuated to force the indenting blade down into the interval between the stitches *d* and *e*, the flat crown shaping 110 surface of the tool engaged and crushed down the crown of the stitch *d* and also engaged the right-hand portion of the crown of the stitch *d*, the resiliency of the material having caused the crown of this stitch to rise 115 slightly after having been previously crushed down by the tool. It is to be noted that while the crown shaping surface of the tool is engaged with the crowns of the stitches *c* and *d*, the interval between these stitches 120 is unobstructed by any portion of the indenting tool. Therefore, when the crowns of these stitches are crushed down by the crown shaping surface of the tool, both the thread of the seam and the leather at the 125 crowns of these stitches are forced into the space previously made by the indenting blade between the stitches to partially obliterate the previously made separation as clearly shown in Fig. 4. The complete and 130

final action of the tool on each stitch is therefore to square or block up the crown of the stitch.

The action of the tool upon the thread of the seam is clearly shown in Figs. 4 and 5. The flat crown shaping surface of the tool when it engages the crown of the stitch flattens or "squashes" out the thread, and at the same time squeezes more or less of the wax out of the thread. The thread at the crown of the stitch is therefore spread out in the manner shown in Fig. 5, and appears coarser and looser in texture than before. Since much of the wax, which gives a rather dark color to the thread, is pressed out of the thread by the action of the indenting tool, the thread at the crowns of the stitches shows its natural white color after the seam is acted upon by the tool. After the margin of the sole is acted upon by the indenting tool it presents a very uniform, striking and attractive appearance, the indentations between the stitches made by the indenting blade still showing slightly on the surface of the welt, the crowns of the stitches having been blocked up in a uniform manner, and the seam resembling very closely a seam sewed with coarse white un-waxed thread.

Having explained the nature and object of the invention, and having specifically described a machine embodying the invention in its preferred form, what is claimed is:—

1. A stitch separating and indenting machine, having in combination, an indenting tool provided with a stitch separating blade and a substantially flat surface arranged perpendicular to the indenting blade and extending entirely over the crown of the stitch in advance of the indenting blade to shape the crown of the said stitch while the indenting blade is indenting the interval between two stitches, and means constructed and arranged to actuate the tool with sufficient force to indent the intervals between the stitches and to shape permanently the crowns of the stitches.

2. A stitch separating and indenting machine, having in combination, an indenting tool provided with a stitch separating blade to enter the stitch intervals, and a substantially flat surface arranged perpendicular to the indenting blade to engage and shape the crowns of two stitches in advance of the indenting blade while the indenting blade is indenting the interval between two

stitches, and means constructed and arranged to actuate the tool with sufficient force to indent the intervals between the stitches and to shape permanently the crowns of the stitches.

3. A stitch separating and indenting machine, having in combination, an indenting tool provided with a blade for insertion in the intervals between the stitches and with a substantially flat surface for engaging and shaping the crowns of two previously separated stitches in advance of the blade while the blade is indenting the interval between two stitches, and means constructed and arranged to actuate the tool with sufficient force to indent the intervals between the stitches and to shape permanently the crowns of the stitches.

4. A stitch separating and indenting machine, having, in combination, an indenting blade for indenting the intervals between the stitches of a finished seam to separate the stitches, crown shaping means to crush down the crowns of the separated stitches while the previously made separations between the stitches are substantially unobstructed to partially obliterate the separations between them, and mechanism constructed and arranged to actuate the indenting blade and the crown shaping means with sufficient force to indent the intervals between the stitches and to shape permanently the crowns of the stitches.

5. A stitch separating and indenting machine, having, in combination, an indenting blade for indenting the intervals between the stitches to separate the stitches, crown shaping means for flattening down the crowns of the stitches after they have been separated, and mechanism constructed and arranged to actuate the indenting blade and crown shaping means with sufficient force to indent the intervals between the stitches and to shape permanently the crowns of the stitches.

6. A stitch separating and indenting machine, having, in combination, means for indenting the interval between two stitches to separate the stitches and for crushing down the crowns of the stitches after they have been separated, and positively acting mechanism for actuating said means.
